(57) **CLAIM**

The ornamental design for a portion of a mesh bin, as shown and described.

DESCRIPTION

FIG. 1 is a perspective view of a first embodiment of a portion of a mesh bin showing my new design; and,

FIG. 2 is a perspective view of a second embodiment of a portion of a mesh bin showing my new design.

The broken line showing of, for example, the rails and mesh portions of the bins, are for illustrative purposes only and form no part of the claimed design.

1 Claim, 2 Drawing Sheets
